CROSSHEAD CONSTRUCTION

Harry A. Hoke, Altoona, Pa., assignor to The Pennsylvania Railroad Company, Philadelphia, Pa., a corporation of Pennsylvania

Application December 29, 1939, Serial No. 311,503

3 Claims. (Cl. 308—3)

This invention relates to crosshead construction for locomotives and, more particularly, to the type supported by guideways provided therefor, while the fundamental object had in view is to provide a novel design of welded crosshead which is easily fabricated.

Another aim of this invention is to furnish a crosshead that is of a more uniform texture, and which is of a denser and stronger character than the conventional cast steel crossheads, while being of less weight and resultantly decreasing the amount of counterbalance necessary in the driving wheels of a locomotive for satisfactory operation.

15 A further object is to effect a substantial reduction in the first cost of crossheads, while in no way reducing their durability and serviceability.

20 A still further object is to provide a crosshead of the above indicated type in which frictional abrasion or "galling" trouble is obviated, while the possibility of blowholes, spongy spots or shrinkage cracks developing is prevented.

25 Other objects and ancillary advantages of this invention will become apparent as the nature thereof is better understood, said invention consisting essentially in the novel form of crosshead hereinafter fully disclosed, illustrated by the accompanying two sheets of drawings of a preferred embodiment and wherein like reference characters are used to designate corresponding parts throughout the several views; while the concluding claims more particularly recite the features of novelty.

30 In the drawings:

35 Fig. 1 is a side view of a locomotive crosshead embodying this invention.

Fig. 2 is a plan as viewed from below the preceding illustration.

40 Fig. 3 is a plan section, taken as indicated by the arrows III—III in Fig. 1.

Fig. 4 is an end elevation of the crosshead as viewed from the right-hand of Fig. 1, or looking towards the left-hand thereof.

45 Fig. 5 is a vertical section on the plane V—V of Fig. 1; and,

Fig. 6 is a similar section on the plane VI—VI in the same figure.

In the following detailed description of the embodiment of this invention shown by the accompanying sheets of drawings, specific terms will be employed for the sake of clarity; but it is to be understood that such terms are used in a descriptive sense and not for purposes of limitation. Each specific term employed herein is in-

tended to embrace all technical equivalents which are susceptible of analogous interpretation.

Referring more in detail to the drawings, the crosshead therein shown comprises a barrel part 1, with integral spaced jaws 2, of comparatively stout metal where the operating loads are greater and between which jaws the driving rod end, not shown, is secured by a suitable wrist-pin engaged through the jaw apertures 3, in accordance with known practice; while the jaws 2 are united across the lower parts by a brace member 4 preferably of the cross-section best understood from Figs. 4—6. This brace member 4 is, preferably, formed with end reductions 5 with forty-five degree sides 6 whereby said member is permanently secured at the inside by fillet welds 7 to the adjoining face portions of jaws 2. Similarly the outer end edge portions of the brace member 4 are united to the lower flat edges 8 of the jaws 2 by fillet welds 9.

United to the upper longitudinal edge 10 of each jaw 2 by inner and outer fillet welds 11, 12, respectively, is a suitably shaped bearer plate 13 of more ductile metal than that forming the crosshead barrel 1 and jaws 2, such plates jointly affording attachment, as by inner and outer fillet welds 14, 15, for the plate or "gib" 16, said "gib" being fitted with upper and lower wear elements 17, 18, in accordance with known practice. In addition, the bearer plates 13 and "gib" 16 are laterally connected by cross-braces 19 united to said plates and "gib" by fillet welds 20, whereby a rigid and comparatively lighter crosshead is ensured with a material saving in first cost

Trouble is frequently experienced due to "galling" between the steel in the front end of the connecting rod, not shown, and the inside of the jaws 2, due to the side pressure caused by lateral movement of the intervening connecting rod end; and to overcome this disadvantage non-ferrous metal such as bronze liners are often cast on the inside of the jaws 2 aforesaid. Unless the cast steel crosshead is preheated before the molten bronze is applied, very small expansion cracks will occur in the steel, which enlarge in service, and eventually destroy the crosshead casting. In accordance with this invention use is made of flange steel orificed liners 21, secured to the inner faces of the jaws 2, concentrically of the apertures 3, by rivets 22, and said liners are segmentally beveled at 23 both at the front and rear portions to provide for the lateral movement of the connecting rod end; or, the bevels 23 are preferably in the nature of opposingly-directed

segmental inclines with the chord edges 23', Fig. 1, paralleling a vertical line through the axis of the apertures 3. These bevels 23 serve to prevent excoriation or "galling" without the use of 5 non-ferrous liners

From the foregoing it will be readily apparent that with a welded crosshead built-up as above described, there is provided a structure wherein the less highly stressed parts which carry the 10 vertical load to the "gib" guides, and which vary from approximately one-tenth to one-fifteenth of the horizontal load produced by the steam pressure on the piston, such as the parts 13, 16 and 19, are fabricated of a more ductile metal 15 of less strength than the parts 1, 2, where the loads are greatest.

Having thus described my invention, I claim:

1. As an article of manufacture a crosshead comprising a barrel with spaced jaws; spaced 20 bearers with intervening cross-braces permanently united to the jaw edges at one side; a transverse member spanning the jaws at the other side; a gib sustained by the vertical bearers

and cross-braces; said bearers, transverse member, cross-braces and gib all being of more ductile metal than the crosshead; and fillet welds uniting all of said parts into a composite unit. 5

2. As an article of manufacture a crosshead comprising a barrel with spaced jaws, said jaws having substantially flat upper and lower edges; vertical bearers with intervening spaced cross-braces sustained by the jaw upper edges; a 10 transverse member spanning the jaw lower edges; a gib mounted on the vertical bearers and cross-braces; said bearers, cross-braces, transverse member and gib all being of more ductile material than the barrel-jaw portion of the crosshead; and fillet-welds unite all of said parts 15 into a composite unit.

3. The crosshead as defined in claim 2, where- 20 in the opposing inner faces of the barrel jaws have orificed liners attached thereto, and said liners are opposingly beveled at their front and back portions respectively to prevent "galling" in service.

HARRY A. HOKE.
